Specification for Design.

Patented June 15, 1920.

Application filed January 24, 1918. Serial No. 213,602. Term of patent 14 years.

To all whom it may concern:

Be it known that I, LAURENCE G. HANMER, a citizen of the United States, residing in the borough of Brooklyn, county of Kings, and State of New York, have invented a new, original, and ornamental Design for an Automobile-Radiator Core, of which the following is a specification, reference being had to the accompanying drawing, forming part thereof.

In the drawings, Figure 1 is a front elevation of the ornamental design for radiator core;

Fig. 2 is a view diagrammatic in character substantially on the line 2—2 of Fig. 1, to show the longitudinal formation of the radiator core; and

Fig. 3 is a view diagrammatic in character substantially on the line 3—3 of Fig. 1 to show the horizontal formation of the radiator core.

I claim:

The ornamental design for an automobile radiator core, as shown.

LAURENCE G. HANMER.
